(57) CLAIM

I claim the ornamental design for a handbag with a stud and stitching pattern, as shown and described.

DESCRIPTION

FIG. 1 is a perspective view of a handbag with a stud and stitching pattern, according to the new design.

FIG. 2 is a front view of a handbag with a stud and stitching pattern, according to the new design.

FIG. 3 is a rear view of a handbag with a stud and stitching pattern, according to the new design.

FIG. 4 is a right side view of a handbag with a stud and stitching pattern, according to the new design.

FIG. 5 is a left side view of a handbag with a stud and stitching pattern, according to the new design.

FIG. 6 is a top view of a handbag with a stud and stitching pattern, according to the new design; and,

FIG. 7 a bottom view of a handbag with a stud and stitching pattern, according to the new design.

The wider broken lines showing the body of the handbag are for the purposes of illustrating environment and form no part of the claimed design.
